Specification for Design.

Patented Jan. 3, 1922.

Application filed March 24, 1921. Serial No. 455,153. Term of patent 7 years.

To all whom it may concern:

Be it known that I, ALFRED W. REISER, a citizen of the United States, and residing at Toledo, in the county of Lucas and State of Ohio, have invented a certain new, original, and ornamental Design for an Arm for Lighting Fixtures, of which the following is a specification, reference being had to the accompanying drawing, forming part thereof.

Fig. 1 is a perspective view of an ornamental arm for lighting fixtures, embodying my new design.

Fig. 2 is a side view of the same.

Fig. 3 is a plan view looking up.

I claim:

The ornamental design for an arm for lighting fixtures, as shown.

ALFRED W. REISER.
